UNITED STATES PATENT OFFICE.

RUTH BURKE STEPHENS, OF LOS ANGELES, CALIFORNIA.

HAIRDRESSING ARTICLE.

Application filed October 15, 1924. Serial No. 743,683.

This invention relates to hair dressing articles, and particularly to a device adaptable for holding the hair in position so that the same will not fall about the face of a person.

The invention is particularly adaptable for use where the hair has been "bobbed" and persons that have "bobbed" hair who are working in restaurants or golfing, or 10 motoring, often find that the hair becomes disheveled and does not stay in place, necessitating their having to use some form of heavy net or a hat to hold the hair. As this is inconvenient and likewise does not lend to 15 the appearance to wear a very heavy net while working or motoring, an object of this invention is to provide a device which is ornamental, of pleasing appearance, acts as a head dress and at the same time holds the 20 hair positively in place.

A further object is the provision of a device which may be readily applied to the head for the purpose of holding the hair against the head and which will not muss 25 the hair and will not shift readily from a position given the same upon the head.

Further objects are the provision of a device which is of simple construction, inexpensive of manufacture, durable, so formed 30 as to be interchangeable to provide various covering effects, and which is generally superior from the stand-point of serviceability.

With the above and other objects in view, 35 the invention consists in the novel and useful provision, formation, construction, association, and relative arrangement of the various parts, members and features, all as shown in certain of its embodiments in the accompanying drawing, described generally, 40 and more particularly pointed out in claims.

In the drawing:

Figure 1 illustrates an application of the invention to the head of a person for the 45 purpose of holding the hair in position;

Figure 2 is a plan view of one form that the invention may assume;

Figure 3 is a modified form of the invention, said view being in plan;

Figure 4 is a fragmentary detail view 50 showing the construction of one form of the invention;

Figures 5, 6, 8 and 9 are enlarged cross sectional views showing various methods of 55 forming the toilet article;

Figure 7 is a fragmentary view showing

a method by which ornamentation may be applied to the invention; and,

Figure 10 is a perspective view of the frame of one form of the invention which 60 includes gripping members.

Corresponding parts in all the figures are designated by the same reference characters.

Referring with particularity to the drawing, I have in Figure 1 shown at A a head 65 the hair upon which has been "bobbed", as shown at 1, with my invention B applied about the hair for holding the hair against the head to prevent the hair from becoming 70 disheveled.

In Figure 2 I have shown a plan view of the device shown in Fig. 1 and designated as B, and in Fig. 3 a modified form of such device designated as C. Said device or 75 devices either B or C consists primarily of a flexible member a encased within ornamentation b. This ornamentation may take the form of a cover of fabric which is Shirred as shown at 2 in Fig. 1 is desired, or left perfectly plain. Said ornamentation may be in the form of an envelope, in that it encloses 80 the member a, and being of fabric, also prevents slipping of the device on the hair as well as protecting the hair against contact 85 with the resilient metallic member. The member a is curvedly bent or U-shaped so that the same when properly covered extends from hair line to hair line around the back of the head, as shown in Fig. 1, the 90 hair line being indicated at 3. The member a in the showing of Figure 4 may comprise a single wire 4 having inherent flexibility and which wire consists of a length 5 which is returnedly and spacedly bent as 95 indicated at 6 with the portions adjacent the ends abutting as shown at 7 and then bent so as to again contact with the portion 5 as indicated at 7a. The ornamentation or outer 100 covering b may then be applied to this wire, and the spacing between the lengths 4 and the lengths 8 hold the covering or ornamentation tightly upon such wire form. In other words, the member a acts as a form for the outer covering or ornamentation b.

In Fig. 5 I have illustrated two lengths of wire 9 and 10 which are formed to be received within and to hold a cover or ornamentation b. 105

Fig. 6 consists of a flexible band 11 within 110 the casing or cover or other ornamentation.

Figure 8 illustrates a band having inher-

ent flexibility and designated as 12, which has its longitudinal edges beaded or curved as shown at 13 and 14, the same being received within the member *b*.

In Fig. 9 the band assumes a sinuous form, as shown at 15. It may be desirable to add various rosettes or other ornamental jewelry to the device such as illustrated in Fig. 1, at 16, in which case the same may be readily secured to the band or wire by sewing through the cover or ornamentation and around the wire or in the case of a flat band such as shown in Figs. 6, 8 and 9 the said band may be perforated as shown in Fig. 7, at 18, thread being passed through such perforations for engagement with the cover.

The form of the device shown in Fig. 3 may comprise an auxiliary or further member *c* in addition to the members *a* and *b*. The member *c* is not of as great length as the members *a* and *b*. The member *c* may comprise a single wire bent in a manner similar to the wire shown in Figure 10 for the member *a* and then soldered to such member *a* or otherwise secured to such member. It is noted that this member *c* has its ends bent inwardly or toward each other.

The purpose of the device C as shown in Figure 3 is in order that the members *a* and *b* may not closely contact with the head of the wearer at the hair line, as in some individuals pressure over the temples has a very disagreeable effect. By use of the member *c* the device C will closely grip the head rearwardly of the hair line and the remaining portion, that is, *a* and *b* will be loose upon the head and yet be tight enough to hold the hair in place.

Several methods may be utilized in the covering of the members *a* and *c*. One preferred method would be to select ornamentation of a width somewhat greater than the width of the members *a* and *c*, with one continuous piece of the ornamentation on the outside of the band *a* and a second piece of the ornamentation on the inside of the band *a* as far as the zone where the member *c* is secured to the member *a*; then doubling

back the ornamentation upon the member *c* 50 on the outside of such member *c*, that is, between the member *c* and the inside of the member *a*, then around the inside of the member *c* and stitching the top and bottom portions of the outside and inside portions 55 of the ornamentation together. Other methods will suggest themselves in accordance with use and requirements.

It is obvious that various changes and modifications and variations may be made in 60 practicing the invention, in departure from the particular showing of the drawing, without departing from the true spirit of the invention.

Having thus disclosed my invention, I 65 claim and desire to secure by Letters Patent:

1. A device for holding "bobbed" hair in place, comprising two parallel and inherently flexible members held in cooperative engagement, one of such members extending 70 from hair line to hair line.

2. A device for holding "bobbed" hair in place, comprising two parallel and inherently flexible members held in cooperative engagement, one of such members extending 75 from hair line to hair line, and the other of such members closely pressing the hair against the head and rearwardly of the hair line.

3. A device for holding "bobbed" hair in 80 place, comprising, two parallel and inherently flexible members held in cooperative engagement, one of such members extending from hair line to hair line; both of such members being provided with ornamentation.

4. A device for holding "bobbed" hair in place, comprising two parallel and inherently flexible members held in cooperative engagement, one of such members extending 90 from hair line to hair line, and the other of such members closely pressing the hair against the head and rearwardly of the hair line; both of such members being provided with ornamentation.

In testimony whereof, I have signed my name to this specification.

RUTH BURKE STEPHENS.
